PATRICK D. RIORDAN, OF NEW YORK, N. Y.

CLOTHES-DRIER.

1,191,998.

Specification of Letters Patent. Patented July 25, 1916.

Application filed November 18, 1915. Serial No. 61,209.

To all whom it may concern:

Be it known that I, PATRICK D. RIORDAN, a citizen of the United States of America, residing at the borough of Manhattan, in the city, county, and State of New York, have invented certain new and useful Improvements in Clothes-Driers, of which the following is a specification, reference being had to the accompanying drawings.

10 This invention relates to improvements in clothes driers; and an object of this invention is to provide a clothes drier which will be simple in construction, comparatively cheap in manufacture and efficient and 15 durable in operation and use.

In the drawings illustrating the principle of this invention and the best mode now known to me of applying that principle, Figure 1 is a front elevation of my new clothes drier; Fig. 2 is a plan thereof; Fig. 20 3 is a section on the line III—III of Fig. 1; Fig. 4 is a section on the line IV—IV of Fig. 1; Fig. 5 is a detail in section showing the manner in which the ends of the wind- 25 lass-rope are secured; Fig. 6 is a section on the line VI—VI of Fig. 2; Fig. 7 is a detail showing the manner in which the controlling ropes are secured to the pulley-block; and Fig. 8 illustrates a modified form 30 in which mechanism is used for turning the clothes drier.

The clothes drier is supported upon a stand having a base-plate *a*, from which rises a post *b* on the upper end of which 35 there is fastened a disk *c* between which and a similar disk *d* there are arranged anti-friction balls *e*. The disks *c*, *d*, and the balls *e* form a substantially frictionless thrust bearing. The upper disk *d* is carried by 40 the lower end of a hollow vertical shaft *f* from the lower end of which there projects a pin *g* that fits snugly in a recess *b'* formed in the upper end of the post *b*. The hollow shaft *f* is in reality an iron tube or pipe the 45 upper end of which is threaded, as shown at *f'*, Fig. 5; and this threaded end *f'* is screwed into a hole *h'* formed in the block *h*. Into the latter there are screwed the three horizontal pipes *i*, *i'*, *i''* and a fourth 50 pipe *i'''* (Fig. 5) which extends in the same direction as the pipe *i''*. The pipes *i*, *i'*, extend in the same direction, as is shown in Figs. 1 and 5, while the other two pipes extend at right angles to the pipes *i*, *i'*. On 55 the outer end of the pipe *i* there is screwed an elbow *j*, into which there is screwed a

vertical pipe *k* the upper end of which carries an elbow *m* into which is screwed one end of a horizontal pipe *n* the other end of which is screwed into a block *o*. Each of the other three pipes radiating from the block *h* supports a similar structure; that is, there are four vertical pipes or standards *k*, *k'*, *k''* and *k'''*, the pipe *k'* joining the horizontal pipes *i'*, *n'*, the pipe *k''* joining the horizontal pipes *i''*, *n''* and the vertical pipe *k'''* joining the lower horizontal pipe *i'''* with the upper horizontal pipe *n'''*. Slidably mounted on each of the vertical pipes *k*, *k'*, *k''*, *k'''*, is a series of rings *p* (Fig. 4) with each of 60 which there is linked another ring *q* that carries a fastener *r* clasped around a rope running parallel and adjacent to one of the vertical pipes; that is, the rope *s* runs parallel and adjacent to the pipe *k*, the rope *s'* runs parallel and adjacent to the pipe *k'*, the rope *s''* runs parallel and adjacent to the pipe *k''* and the rope *s'''* runs parallel and adjacent to the pipe *k'''*. The ropes *s*, *s''*, 65 are in reality parts of a single rope which passes through the eye *t* of the pulley-block *u* (Fig. 7) and the ropes *s'*, *s'''*, are likewise parts of a single rope which also passes through the eye *t*. As is clearly shown in Fig. 7, the ropes may be bound together by 70 a cord *s* just above the eye *t*. Each of the ropes *s*, *s'*, *s''*, *s'''*, passes over two pulleys; that is, the rope *s* passes over the pulleys *v*, *w*, the rope *s'* passes over the pulleys *v'*, *w'*, the rope *s''* passes over the pulleys *v''*, *w''*, and the rope *s'''* passes over the pulleys *v'''*, *w'''*. The pulleys *w*, *w'*, *w''*, *w'''*, are mounted in brackets *x* which are fastened to the upper block *o*, while the pulleys *v*, *v'*, *v''*, *v'''*, are mounted, respectively, in brackets *y*, *y'*, *y''*, *y'''* that are fastened, respectively, to the horizontal pipes *n*, *n'*, *n''*, *n'''''*.

As shown in Fig. 1, a series of clotheslines *z* is provided, which clotheslines are horizontally-disposed (Figs. 1 and 2). Each 100 clothesline *z* passes or is clipped, free to slide, through a set of four rings *q* and carries at one end a ring *z'* with which engages a snap-hook *z''* carried by the other end of the clotheslines *z*. Over these connecting 105 parts *z'*, *z''* there is drawn a tube *z'''* which serves to prevent smutching of the clothes by the metallic connecting parts *z'*, *z''*.

To raise the clotheslines *z* and the clothes hung thereon, the following mechanism is 110 provided: Depending from the tubular frame-member or pipe *i'*, there is a pair of

hangers 2 the lower ends of which carry a tubular bearing 3 through which passes a windlass-shaft 4 one end of which carries a drum 5 and the other end of which is provided with a crank 6. The inner end of the windlass shaft 4 passes through the hollow shaft or pipe f' and is fastened in place by a nut 7. The outer end of the windlass shaft 4 carries a ratchet-wheel 8 that is engaged by the toe of the pawl 9 pivoted on a disk 10 fastened to the tubular bearing 3. To the drum 5, there is fastened one end of a windlass rope 11 which passes over the pulley 12 and the other end of which passes through a plug 13 and is tied in a knot 14. The plug 13 is screwed into the end of the hole h' opposite the threaded end f' of the hollow shaft f' (Fig. 5).

Referring to the manually-operated clothes drier illustrated in Fig. 1, the housewife first fastens the wet clothes upon the topmost clothesline z , which is raised to the proper height by turning the shaft 4 by means of the crank 6. When the shaft 4 turns, the drum 5 likewise turns; and, when this rotary motion is in the proper direction, the windlass cable 11 is wound upon the drum 5 and this winding-up of the cable 11 causes the pulley 12 and the pulley-block u to be lowered, thereby raising the portions of the ropes s , s' , s'' , s^x , that are vertical and adjacent to the vertical frame members k , k' , k'' , k^x , respectively. When these ropes move upwardly, they carry upwardly with them the fasteners r and, through the latter, the rings q , p ; and, as the rings q move upwardly, the clotheslines z are raised. The pawl 9 holds the clotheslines and the clothes thereon in raised position by preventing the turning of the shaft 4 in a direction opposite to its winding-up direction. Upon pushing laterally against the tubular bearing 3, the clothes drier proper may be turned on its thrust bearing c , d .

In Fig. 8, there is illustrated a form of this invention in which mechanical means are provided for rotating the clothes drier. To the post b'' , there is fastened, as by the set-screw 15, a bracket 16 which carries an electric motor 17 on the armature-shaft 18 of which there is mounted fast a bevel gear 19 that meshes with a bevel gear 20 formed on the collar f'' which is integral with the shaft f' . Between the head b^x of the post b'' and collar f'' , there are interposed anti-friction balls f^x . When the motor 17 is driven, the gears 19, 20 set the shaft f' in rotation and the clothes carried by the drier are whirled through the air.

The parts being in the position shown in Fig. 1, in which the uppermost clothesline z is shown in clothes-receiving position, the housewife fastens the wet clothes upon this uppermost clothesline. It is to be observed that the cables s , s' , s'' , s^x are collapsed or

folded at their lower ends, that is, they are not taut and the three lowermost clotheslines z are shown lying upon one another. Having filled the uppermost clothesline z with washed linen, the housewife seizes the crank 6, rotates the windlass shaft 4 and turns the windlass drum 5 so as to wind thereon the windlass rope 11. The winding-up of the windlass rope 11 causes the sheave 12 to be pulled down and the cables s , s' , s'' , s^x , to be pulled up, the rings p sliding along the guiding frame members k , k' , k'' , k^x . When the second clothesline z has reached the clothes-receiving position, the housewife stops turning the crank 6 and the windlass shaft 4 is held against retrograde rotation by means of the engagement of the pawl 9 with the ratchet teeth 8. Of course, the housewife will, in putting the wet clothes on the clothesline z rotate the frame upon the thrust bearing c , d , by using the windlass shaft 4 as a lever. After each clothesline z has been raised successively into clothes-receiving position and the wet clothes have been fastened to these clotheslines z , the housewife may continuously rotate the frame and the clotheslines and clothes carried thereby by allowing current to energize the electric motor 17, whereby the drying of the clothes will be greatly accelerated, as will be readily understood. After the clothes have been dried, the current is cut off from the electric motor and the frame is consequently brought to rest. The dry clothes are then taken from off the lowermost clothesline z ; and, by raising the pawl 9, the next uppermost clothesline may be brought into clothes-receiving position, the weight of the dry clothes assisting the operator to pull down the cables s , s' , s'' , s^x . The pawl 9 is allowed to fall and engage the ratchet-teeth 8, whereby the clothesline now in clothes-receiving position is held therein. After the next to the last clothesline has been stripped of its dry clothes, the pawl 9 is raised again and the next clothesline z is allowed to fall to clothes-receiving position, after which the pawl 9 is again engaged with the ratchet-teeth 8. After the clothes have been removed from all the clotheslines z , these clotheslines are left lying one above the other at the bottom of the frame, the cables s , s' , s'' , s^x , collapsing or folding as is shown in Fig. 1.

In accordance with the provisions of the patent statutes, I have described the principle of operation of my invention, together with the apparatus which I now consider to represent the best embodiment thereof; but I desire it understood that the apparatus shown is only representative and that the invention may be carried out by other means. Thus, by means of the snap hook z'' , the operator is enabled to disconnect readily the ends of the clothesline z and thereby to ex-

clude the possibility of the rupture thereof by the shrinkage of the same due to its becoming saturated with rain water; yet the snap-hook fastening may be dispensed with 5 and the clothesline s made long enough to allow for such shrinkage, in which case the ends of the clothesline may be fastened by a device such as the fastener r . The raising- and-lowering cables may be so rove that the 10 cables s , s' , will form parts of a single cable, in which case the cables s'' , s''' , will form parts of the other cable; and the binding-rope s may be dispensed with. Means other than the electric motor 17 may be provided 15 for imparting a whirling motion to the shaft f .

I claim:

20 A clothes-drier including a stand; a frame rotatably mounted thereon; a windlass carried by said frame; a series of substantially horizontally-disposed clothes-car-

rying lines; substantially vertically-disposed collapsible cables which carry said lines; a sheave to which the ends of said cables are attached; and a rope that is rove through 25 said sheave and one end of which is fastened to said frame and the other end of which passes around said windlass, the turning of which windlass winds up said rope and shifts said sheave and raises said lines successively into clothes-receiving position and 30 into spaced relation with respect to one another.

Signed at the borough of Manhattan, city, county and State of New York, this eighth 35 day of November, A. D. 1915, in the presence of the two undersigned witnesses.

PATRICK D. RIORDAN.
